UNITED STATES PATENT OFFICE.

GEORGE E. POGGEL, OF LOUISVILLE, KENTUCKY, ASSIGNOR TO ADVANCE MANUFACTURING COMPANY, OF LOUISVILLE, KENTUCKY, A CORPORATION OF KENTUCKY.

APPARATUS FOR SEASONING AND RECTIFYING PAPER STOCK.

Application filed December 17, 1927. Serial No. 240,876.

The present invention relates to improvements on the apparatus for seasoning and rectifying paper stock set forth in my Patent No. 1,325,044 dated December 16, 1919.

- 5 My improvements relate, first, to means whereby the apparatus may be kept in substantially continuous operation, thus saving time and increasing output; improved panels which can be adjusted so that they may be
 10 brought up to the sides of the suspended paper stock and thus insure the direct upward passage of the air between the sheets and preventing escape of the air laterally, hence resulting in rapid conditioning of the paper;
 15 improved means for effecting ventilation, whereby humidity and temperature may be controlled as desired; an improved arrangement of a plurality of fans and groups of heating units whereby the temperature is
 20 varied and the humidity lowered according to requirements of the paper stock, weather conditions, and condition of the temperature in the room; arrangement and relationship of the means for suspending the paper stock,
 25 and the portable cabinet carrying the fans, heating units, and panels, whereby only a relatively small amount of floor space is required for the apparatus, the treatment and handling of the stock is facilitated and it is
 30 made possible to practically continuously operate the apparatus.

Other objects and improvements over my patent will appear from the following specification of construction and operation, the
 35 novel features and combinations of the apparatus being set forth in the appended claims.

In the accompanying drawings:

- Figure 1 is a side elevation looking toward
 40 the exterior of the apparatus, full lines representing the cabinet in one of its positions for treatment of the paper stock, and dotted lines representing the cabinet in the other of its operative positions;
 45 Fig. 2 is a longitudinal section showing the cabinet in the full line position of Fig. 1, arranged for treatment of paper stock, illustration of only a few sheets being given;

Fig. 3 is a cross sectional view at right angles to Fig. 2, dotted lines representing the suspended paper stock undergoing treatment;

Fig. 4 is a front elevation of the cabinet in closed position and ready for use;

Fig. 5 is a horizontal section on the line 55 5—5, Fig. 2;

Fig. 6 is a detail sectional perspective view showing the co-operating parts on the top and middle sections of one of the vertically slideable sectional doors for the cabinet;

Fig. 7 is a horizontal detail section showing the manner of guiding and mounting the sectional door; and

Fig. 8 is a diagram of the electric appliances and wiring.

The cabinet 1 has supporting wheels 2 which travel on flanged rails, enabling the cabinet to be shifted from the full line position of Fig. 1 to the dotted line position thereof and vice versa.

Unlike the cabinet of the apparatus of my Patent No. 1,325,044, it has no top of its own. When the cabinet 1 is in its respective positions, it is located underneath one or the other of the stationary or permanent tops 4, 5, said top then serving as the top of the cabinet.

The stationary or permanent tops 4, 5, are rigidly suspended from the ceiling 6 of the room in which the apparatus is located by rods or hangers 7 and there may be provided suitable braces as shown at 8, if desired. The tops 4, 5, are preferably interbraced by the horizontal angle iron bars 9 secured to the sides of the tops by the bolts 10. The framework thus provided for the tops 4, 5, holds them in suspended, rigid, horizontal position, spaced or separated from each other, but arranged above the track or rails 3 so that the cabinet may be shifted from beneath one of the tops to the position beneath the other of said tops and when located beneath one of the tops, the open top of the cabinet lies outside of, and closely adjacent to, the depending, braced skirt or apron 11 as best illustrated in Fig. 3, effectually sealing the joint between the side walls of the cabinet 1 and the depending side walls of the top 4, or 5, as the case may be.

Each top is provided with any suitable, or well-known, means for suspending the sheets of paper stock 12 as illustrated in Figs. 2 and 3. In Fig. 2 only a few of the sheets of paper stock 12 are illustrated but it will be understood that the cabinet is well filled with these suspended sheets. I have illustrated a well-known form of paper suspending clamp at 13, said clamp being adjustably carried by cross bars 14 secured to the tops 4, 5.

Each of the tops 4, 5, is provided with a ventilator whose purpose will appear herein-after. This ventilator may assume different forms but, as shown, it consists of a pair of hinged doors 15, 16 extending practically the entire length of the top and arranged to overlap each other. The respective doors may be closed, or partially or fully opened by manipulating pull ropes, wires or chains 17, 18 so that either one or both of the doors constituting the ventilator may be set as desired. The ventilator of each top is controllable independently of the ventilator of the remaining top. At the front and rear of each top are depending doors or flaps 19, 20 which are in lowered position when the cabinet is closed as shown in Figs. 1, 2, and 4 to overlap the front and rear sectional doors of the cabinet. When, however, it is desired to shift the cabinet from beneath its top, or to arrange the cabinet beneath the remaining top, these doors may be elevated as shown in connection with the top 5, Fig. 1. Any suitable means may be provided for this purpose; I have illustrated a pull chain or rope 21 in each instance so that each flap may be arranged as desired.

At the ends of the cabinet there are vertically slidable doors comprising two sections 22, 23. The lower part of the cabinet is closed by a fixed wall 24. The sections 22, 23 are adapted to slide up and down in guides 25 at the corners of the cabinet, as best illustrated in Fig. 7. The guides 25 may be constructed as desired but, as shown, they are of channel form and are composed of angle iron strips connected to the sides of the cabinet, and flat strips with intermediate filler strips connected to the angle iron strips. The door sections 22, 23 have their edges projecting into the guides and one or both of said door sections is provided with retaining metal strips 26 which straddle the guides 25 and insure a snug fit as between the door sections and the cabinet.

The section 23 is raised by the section 22, when the latter is elevated, by reason of the co-operating strips at the overlapping edges of said door sections as illustrated in Fig. 6. This result may be accomplished in different ways but, as shown, the sections 22 and 23 are provided with angle iron strips 27, 28 arranged horizontally and secured to the overlapping edges of said sections. The section 23 has an angle iron strip 29 overlying the upper edge of said section and riveted at 30 to the strip 27 and the section 23. The section 22 has a metal strip 31 riveted at 32 to the lower edge of the said section and to the angle iron strip 28.

The aforesaid construction provides engageable members on the sections 22 and 23 by which the section 23 is elevated by, and travels as a unit with, the section 22 when the section 22 is raised sufficiently, whereas when

the section 22 is lowered, the section 23 is lowered with it. The sections 22 and 23 can be raised to the full height shown in Figs. 2 and 4, or lowered to lie in front of the fixed section 24, thus enabling the cabinet to be closed at its ends, or opened up thereat.

Hand lifts 33 are provided on section 22 to enable the operative to elevate or lower the sections 22, 23. Latches 34 are adapted to hold the doors in elevated position.

If desired, other means may be used for raising and lowering the door sections.

The construction shown in Fig. 6 serves the purpose of a relatively tight joint between the sections of the doors so that the air is confined within the cabinet when the paper is undergoing seasoning.

For the purpose of counterbalancing the door sections 22, 23, so that they may be easily raised or lowered, counterbalancing ropes or cables, pulleys, and weights are provided, of which cables 35 are connected to the angle iron pieces 28, run over pulleys 36 mounted on the cabinet 1 and are provided with counterweights 37. Other cables 38 are connected to the guide straps 26, run over pulleys 39 carried by the outside of the cabinet 1, and are provided with counterweights 40 located on the outside of the cabinet.

The side panels are shown at 41, said panels having feet or supports 42 which are provided with slots receiving the edges of the horizontal flanges 43 at the upper edges of the fixed sections 24. This mounting for the panels 41 enables them to be slid laterally toward or away from each other so that they may be brought snugly up against the edges of the sheets 12 of paper stock, regardless of the width of said sheets. The panels 41, when thus brought up against the edges of the sheets 12, necessitate the air currents blown upwardly between the sheets being brought into contact with the surfaces of the sheets because such air currents cannot escape laterally between the sheets. This results in greater efficiency than is possible with the hinged panels set forth in my Patent 1,325,044 where the inclined position of the panels permits a part of the air to divert laterally before it has risen to the full height of the sheets of paper.

With the present panels, this greater efficiency is obtained regardless of the width of the sheets 12.

Between the panels 41 and the sides of the cabinet 1 are spaces or diving flues 44 down which the air currents pass, after they have traversed the sheets 12 from the bottom to the top edges thereof, thereafter being returned upwardly between the panels to re-traverse the sheets, thus keeping up the cycle which is set forth and claimed in my Patent 1,325,044.

To eliminate dead air pockets and to facil-

itate the travel of the air currents, the tops 4, 5 are of more or less dome shape, being provided with arched corners 45. The lower part of the cabinet is provided with baffle plates 46 or formed in general deflecting shape so that the air currents descending the diving flues 44 to the bottom of the cabinet will be deflected upwardly.

In the bottom of the cabinet 1 is a ventilator, preferably similar to the ventilator 15, 16, comprising the hinged doors 47, 48 which overlap and are adapted to be opened upwardly. Any suitable means, not shown, may be provided for setting these ventilator sections 47, 48 in any desired position, either fully closed, fully opened, or in intermediate position and each of them may be operated independently of the other one.

In my Patent 1,325,044 I have proposed the use of a single electric fan combined with a plurality of electric heaters located in the lower part of the cabinet and used to heat the air and blow it upwardly between the sheets of paper stock.

As a part of the present improvements, I provide a plurality of electric fans located above the electric heaters and use electric heaters which are arranged in groups, each group having its own controlling switch, as shown in the diagram, Fig. 8. The number of heaters in each group and the total number employed, as also the number of electric fans, will vary according to the size of the installation. The provision of a plurality of heating units arranged in different controllable groups, in connection with a plurality of fans, enables different air temperatures to be attained, according to the number of groups of heaters which are utilized. Thus, it is within the control of the operative to meet the existing conditions as to temperature and humidity so that the most rapid and thorough seasoning and rectifying effects may be obtained.

The electric fans appear at 49. Beneath the fans are the electric heating units 50 comprising insulated bars of resistant material arranged in groups bridged on the main circuit 57 and the branches 52, 53, 54 for the respective switches 55, 56, 57. The main circuit appears at 58 and supplies the current direct to the fans 49. The main control switch appears at 59 and the electric supply circuit at 60.

When the switch 59 is closed, all of the fans 49 are set in operation but as many of the heating units 50 may be employed as found desirable, the others being cut out through the control at the switches 55, 56, 57.

The apparatus is adapted to carry out the process set forth in my Patent No. 1,325,044 and is used in the following manner.

Assuming that the cabinet 1 is in the position shown by dotted lines, Fig. 1, the sheets 12 of paper stock which are to be seasoned

and rectified are suspended from the clamps 13 as shown in Figs. 2 and 3, from the cover 4. The panels 41 are then moved laterally toward each other to bring them snugly up against the edges of the paper stock 12. The doors 22, 23 are then raised and latched. The fans 49 are set in operation by closing the switch 59 and, according to requirements, as many of the electrical heating units 50 are switched on by the use of any 75 or all of the switches 55, 56, 57 as may be necessary. The air is blown upwardly between the sheets 12 and then dives down the flues 44, carrying out the process set forth in my Patent 1,325,044. The air diving 80 down the flues 44 is re-heated and forced upwardly by the fans 49, the cycle continuing as long as necessary to effect the desired results.

As soon as the cabinet is closed when in 85 the full line position of Fig. 1, and the fans and heaters set in operation, the operative may immediately begin to suspend paper from the clamps provided in the cover 5 so that the cover 5 may be fully loaded while 90 the paper suspended from the cover 4 is being conditioned. Thus, the operative loses no time waiting for the paper to be seasoned and by the use of the two covers 4, 5, arranged adjacent each other, the operation of 95 the apparatus may be kept substantially continuous.

When the paper suspended from the cover 4 and enclosed in the cabinet 1 has been properly conditioned, the flaps or upper doors 19, 20 of the cover 4 may be raised and the sectional doors 22, 23 at both ends of the cabinet lowered, whereupon the cabinet 1 may be rolled from the position shown in full lines in Fig. 1 to the position shown in dotted 100 lines in Fig. 1, the flap doors 19, 20 of the cover 5 having been raised to enable the cabinet to be located beneath cover 5. The sectional doors 22, 23 may then be raised and the flap doors 19, 20 of the cover 5 lowered 105 to completely enclose the suspended paper stock carried by the cover 5, the panels 41 having been previously adjusted to bring them up against the edges of the suspended paper.

The operative then sets the fans and heaters in operation, when the closed cabinet is in position to treat the paper suspended by the cover 5, and directs his attention to the seasoned and rectified paper stock 110 remaining suspended from the cover 4. This stock having been removed, fresh unconditioned, paper stock is suspended from the clamps carried by the cover 4. Thus, by the provision of two fixed covers, 4, 5, relatively 115 arranged so that the cabinet can be moved to position it under either one of them, I do away entirely with the removable cover set forth in my patent and greatly increase the capacity of the apparatus.

The efficiency of the apparatus is increased by reason of the employment of the adjustable panels 41 and the quick-acting doors, as also the employment of a plurality of 5 fans and groups of heating units, more or less of which may be used according to requirements. Furthermore, the output of the apparatus during a given period is greatly increased. If the ventilators 15, 16 and 47, 10 48 are kept closed while the paper is being conditioned, the percentage of humidity is lowered while the heaters are in use. If these ventilators are opened, the temperature of the paper may be reduced, bringing it down 15 to the same temperature as existing in the room.

The use of a plurality of fans affords an even distribution of the air circulation which quickens the process of bringing the paper 20 stock into equilibrium with the temperature and humidity existing in the room, provided no heat is used. If heat be used, the humidity content of the paper stock may be lowered to any desired extent and constitutes a practical 25 means for reducing the temperature in such a manner that the paper stock does not attract back to itself the humidity existing in the room when it is removed from the machine.

30 Thus, the user can employ heat or dispense with it, as conditions may warrant.

As previously explained, the adjustable panels 41 prevent the air currents from spreading laterally and cause them to travel 35 upwardly past the entire surfaces of the sheets.

What I claim is:

1. In an apparatus for seasoning and rectifying paper stock, the combination with a 40 movably mounted cabinet, of a plurality of covers or tops therefor, each of which is provided with means for suspending sheets of paper, said cabinet being adapted to be positioned under any one of said tops or covers 45 for the purpose of enclosing the paper suspended from said top or cover.

2. In an apparatus for seasoning and rectifying paper stock, the combination with a movably mounted cabinet, of a plurality of 50 covers or tops therefor, each of which is provided with means for suspending sheets of paper, said cabinet being adapted to be positioned under any one of said tops or covers 55 for the purpose of enclosing the paper suspended from said top or cover, and means for alining the cabinet beneath the respective tops or covers.

3. In an apparatus for seasoning and rectifying paper stock, the combination with a 60 movably mounted cabinet, of a plurality of covers or tops therefor, each of which is provided with means for suspending sheets of paper, said cabinet being adapted to be positioned under any one of said tops or covers 65 for the purpose of enclosing the paper sus-

pended from said top or cover, and a track for guiding the cabinet in its movements from beneath one of the covers to beneath another of the covers and for alining said cabinet in relation to the respective covers so that it 70 will be adapted to enclose the paper suspended from the cover.

4. In apparatus for seasoning and rectifying paper stock, the combination with an open-topped cabinet, of a plurality of paper-suspending tops, any one of which may be used to cover the open top of said cabinet when said cabinet and tops are relatively shifted.

5. In an apparatus for seasoning and rectifying paper stock, the combination with an open-topped cabinet, of a plurality of stationary paper-suspending tops respectively adapted to serve as covers for said cabinet when it is located under them, said cabinet 80 being shiftable for disposition under any one of said stationary tops for the purpose of enclosing and treating the paper suspended by said top.

6. In an apparatus for seasoning and rectifying paper stock, the combination with an open-topped cabinet, of a plurality of stationary paper-suspending tops respectively adapted to serve as covers for said cabinet when it is located under them, said cabinet 90 being shiftable for disposition under any one of said stationary tops for the purpose of enclosing and treating the paper suspended by said top, and means for guiding the cabinet in its travels from beneath one top to 95 beneath the other top.

7. In an apparatus for seasoning and rectifying paper stock, the combination with a plurality of suspended paper-suspending tops beneath each of which is an open or 105 clear space, of an open-topped cabinet adapted for use under any one of said tops, the selected top then covering the open top of the cabinet, and means whereby the cabinet and the group of tops may be relatively 110 shifted.

8. In an apparatus for seasoning and rectifying paper stock, the combination with a plurality of paper-suspending tops beneath each of which is an open or clear space, of an 115 open-topped cabinet adapted for use under any one of said tops, the selected top then covering the open top of the cabinet, the cabinet being shiftable for disposition beneath any one of said tops, the selected top then 120 constituting a cover for the cabinet.

9. In an apparatus for seasoning and rectifying paper stock, the combination with a paper suspending cover, of an open-topped and open-ended cabinet adapted to enclose 125 paper suspended by said cover, and doors for the open ends of said cabinet, said cabinet being bodily movable laterally in relation to said cover to expose the paper suspended by the cover.

10. In an apparatus for seasoning and rectifying paper stock, the combination with a paper suspending cover, of an open-topped cabinet adapted to enclose paper suspended by said cover, doors for the cabinet, said cabinet being movable in relation to said cover, and doors carried by the cover which are adapted to overlap the doors of the cabinet.
11. In an apparatus for seasoning and rectifying paper stock, the combination with a cover or top having means adapted for the suspension of the paper stock, and a cabinet which is shiftable under, or away from, said cover, of panels or supplemental walls contained within the cabinet and adapted for bodily lateral adjustment to be brought against the edges of the suspended paper stock in said cabinet.
12. In an apparatus for seasoning and rectifying paper stock, the combination with a cover or top having paper suspending means, of a cabinet which is shiftable under, or away from, said cover, rigid panels or supplemental interior walls arranged vertically and supported in laterally adjustable manner at their lower parts within the cabinet so they can be positioned adjacent the edges of the paper stock suspended therein, a plurality of fans carried by the cabinet and arranged to direct air current upwardly between the sheets of paper stock and between the panels or supplemental walls, and a plurality of controlled heating units in said cabinet for bringing to the desired temperature the air which is blown by said fans.
13. In an apparatus for seasoning and rectifying paper stock, the combination with a cover or top having means for suspending sheets of paper, of a ventilator carried by said cover or top, a movably mounted cabinet adapted to be positioned under said cover or top to enclose the paper suspended by the cover, or to be removed from under said cover, a ventilator carried by said cabinet, paper-heating means carried by said cabinet, and a fan carried by the cabinet for circulating the heated air within the cabinet.

In testimony whereof I affix my signature.

GEORGE E. POGGEL.
